UNITED STATES PATENT OFFICE

ALBERT S. HOWELL, OF CHICAGO, ILLINOIS, ASSIGNOR TO THE BELL & HOWELL COMPANY, OF CHICAGO, ILLINOIS, A CORPORATION OF ILLINOIS

PHOTOGRAPHIC-PRINTING MACHINE

Application filed August 17, 1927. Serial No. 213,549.

My invention relates particularly to machines for printing motion picture film although not limited to this use alone.

One of the objects of the invention resides 5 in the provision of means whereby a plurality of longitudinal sections of a photographically sensitized strip, such as an unexposed positive motion picture film, may be exposed to or printed from different photographic 10 printing or negative strips so that a plurality of subjects, preferably related, and particularly related visual sound records and motion pictures, may be printed on the positive, all with a view toward convenience, high 15 production, and quality in the production of a single projection or record medium bearing related visual sound records and motion pictures for use in the exhibiting of the so-called talking motion pictures.

With this object in view my invention consists in certain features of novelty in the construction, combination, and arrangement 20 of parts by which the said object and certain other objects, hereinafter appearing are effected, all as fully described with reference 25 to the accompanying drawings and more particularly pointed out in the appended claims.

In the said drawings—

Figure 1 is a front elevation of a motion picture film printing machine embodying my invention;

Figure 2 is an enlarged partial section on the line 2—2 of Figure 1;

Figure 3 is a section on the line 3—3 of Figure 2;

Figure 4 is a partial section on the line 4—4 of Figure 5, hereinafter described;

Figure 5 is an enlarged partial section on the line 5—5 of Figure 1;

Figure 6 is a face view of a portion of a positive film printed on the machine;

Figures 7 and 8 are face views of portions of the negative films used in printing the positive film;

Figure 9 is a partial section on the line 9—9 of Figure 10, hereinafter described;

Figure 10 is an enlarged front elevation of a portion of the machine with a part thereof removed;

Figure 11 is an enlarged face view of the exposure aperture face guide member and related parts of one of the exposure devices, hereinafter described;

Figure 12 is a section on the line 12—12 of 55 Figure 11;

Figure 13 is an enlarged partial interior view somewhat similar to Figure 3 with parts broken away and in section, on the line 13—13 of Figure 11.

Like characters of reference indicate like parts in the several views.

In the said drawings, 1 designates a pedestal which supports the machine, and arranged at the top of this pedestal is a lamp chamber 2 in which is mounted a source of photographic light in the form of an incandescent electric lamp 3. See Figures 1 and 5. A portion of the frame of the machine in front of the lamp is bored horizontally in a forwardly and rearwardly extending direction, as designated at 4, and communicates radially with the lamp chamber through a light passage 5. See Figures 4 and 5. The front end of the bore 4 is closed by a cover member 6 secured therewith, and the rear end of this bore is closed in a manner unnecessary to be described. Disposed in the bore 4 in coaxial relation therewith is a revolvably mounted film feed sprocket comprising two axially spaced peripherally toothed wheels 7 and an axial spindle 8 extending therebetween. The light passage 5 is aligned with the plane of the space between the wheels 7; and the frame is provided with an opening communicating with the bore 4 between the wheels 7 and disposed in substantially diametrically opposite relation with respect to the light passage 5. A motion picture film guide is associated with this opening and consists as follows. A pair of stationary film face guide plates 9 are mounted on the frame and extend in said opening in tangential relation with the wheels 7 and have their adjacent ends spaced to provide an exposure opening. An opposing film face guide member 11 is mounted on a pivoted arm 12 for movement into and out of film guiding relation with the guide plates 9, this guide member being so mounted to open the guide 100

for the lacing and unlacing of film therein and to form with the plates 9, when it is in film guiding relation therewith, a film guide for retaining film therein in engagement with the sprocket comprising the wheels 7 for the feeding of the film. Accordingly the intermediate portion of the film guide face of the guide member 11 is of concave form corresponding with the periphery of the sprocket comprising the wheels 7, and the end portions of this face are tangent thereto, the plates 9 being parallel with these end portions when the guide member 11 is in film guiding relation therewith. The guide member 11 is releasably secured in film guiding position in a manner unnecessary to be described.

The guide so formed is adapted to guide superposed printing or negative and photographically sensitized or positive films, respectively designated at 13 and 14, engaged on the aforementioned sprocket, comprising the wheels 7, for the feeding of these films in printing relation through the guide and past the exposure aperture between the wheels 7 provided by the spacing of the plates 9, where they are subjected to the printing light provided by the lamp 3 in the lamp chamber 2. The lower edge of this exposure aperture is formed by a stationary member 15 secured to the frame and extending angularly corresponding with the wheels 7 and between the same and forming with its upper edge the lower edge of this exposure aperture. The upper edge of this exposure aperture is formed by a movable shutting member 16 extending angularly corresponding with the wheels 7 and between the same and forming with its lower edge the upper edge of this exposure aperture. This shutting member 16 is mounted for angular adjustment coaxially of the wheels 7 to vary the aforementioned exposure aperture longitudinally of the aforementioned guide whereby to vary the exposure of the films in the guide as they are fed therethrough at a uniform rate by uniform rotation of the sprocket comprising the wheels 7. Accordingly a shaft 17 is journaled in the bore of a coaxially bored sleeve 18 which in turn is journaled in coaxial relation with the wheels 7 in an extended bore through the cover member 6, and an arm 19 is secured on the inner end of the shaft 17 and extends over the periphery of the adjacent wheel 7 and is secured with the shutter member 16 whereby the shutter member is carried for angular movement coaxially with the wheels 7. An arm 20 is secured on the outer end of the shaft 17 for adjusting the shutter member 16, and this shutter member is adjustably secured in position by a suitable releasable securing device 21.

The light passage 5 is partially blocked by a shield 22 which is provided with a light

aperture 23 between the wheels 7 across which is disposed a ground glass 24 for diffusing the light from the lamp 3. Another shutter 25 is angularly movable coaxially with the wheels 7 for varying the light passing from the aperture 23 to the aforementioned guide, and is mounted for such angular movement by means of an arm 26 secured on the inner end of the sleeve 18 and fast at its outer end with the shutter 25. An arm 27 is secured on the outer end of the sleeve 18 for the adjustment of the shutter 25. Thus is provided another means for varying the exposure of the films as they are fed through the aforementioned guide for purposes hereinafter described.

The frame of the machine extends upwardly from the rear of the portion thereof having the bore 4 therein in the form of a gear casing 28 at the upper end of which is disposed another exposure device which will now be described. See Figures 1, 2, 3, and 9 to 13 inclusive.

A shaft 29 is revolvably mounted on the gear casing adjacent its upper end and is disposed on a forwardly and rearwardly extending axis. See Figures 2 and 3. The shaft 29 projects from the gear casing 28 forwardly and is provided at its projecting front end with a film feed sprocket comprising two axially spaced peripherally toothed wheels 31 and a portion of the shaft 29 extending axially therebetween and fast therewith. The wheels 31 have the peripheral portions thereof projected toward each other, as designated at 32, and a stationary closure member 33 of generally circular form is disposed between the wheels 31 in coaxial relation therewith and underlies the projected portions 32 of the wheels 31 and forms a light tight lamp enclosure therewith. The closure member 33 is secured with the frame of the machine by means of a generally semi-circular extension 34 thereof projecting from the closure member between the wheels 31 and outwardly thereof and secured outwardly of these wheels to a corresponding semi-circular portion 35 of the gear casing 28 disposed outwardly of the inner wheel 31. Thus is provided a compact and simple construction providing a lamp chamber or enclosure between the revolvable wheels 31.

The extensions 34 and 35 are disposed at the upper portion of the closure member 33, and secured to a downwardly facing horizontal surface at the lower portion of this closure member is a film face guide plate 36 disposed between the wheels 31. This plate has a downwardly facing film face guide surface which is composed of an intermediate longitudinally extending convex portion 37 corresponding with the periphery of the sprocket comprising the wheels 31 and end portions 38 tangent to said intermediate portion. An opposing film face guide member

39 is pivotally mounted, as designated at 41, for movement into and out of film guiding relation with the guide plate 36, this guide member being so mounted to open the guide for the lacing and unlacing of film therein, and to form with the guide plate 36, when it is in film guiding relation therewith, a film guide for retaining film therein in engagement with the sprocket comprising the 5 wheels 31 for the feeding of the film. The film face guide surface of the guide member 39 corresponds with the film face guide surface of the guide plate 36, and the intermediate portion of the film face guide surface of the guide member 39 is formed of a separate part 42 which is spring pressed against film in this guide by a spring 43 to insure proper printing relation of superposed films therein at the exposure opening 10 of this guide hereinafter described. The guide member 39 is releasably secured in film guiding position in a manner unnecessary to be described.

The guide formed by the guide plate 36 25 and the guide member 39 is adapted to guide superposed negative and positive films, comprising the aforementioned positive film 14 and another negative film 44, engaged on the sprocket, comprising the wheels 31, for 30 the feeding of these films in printing relation through this guide and past the exposure aperture thereof, hereinafter described, between the wheels 31 for printing upon the positive film 14 from the negative film 44.

35 See Figure 13.

This last mentioned exposure aperture is formed as follows. See Figures 11, 12, and 40 13. The guide plate 36 is provided with a stepped concave formation 45 facing oppositely from the film in the corresponding guide, and the deep part of this formation is disposed immediately adjacent the inner wheel 31 and continues the arc of the convex surface 37 of the plate 36 and forms the exposure opening for the last mentioned guide. 45 See particularly Figures 11 and 13. A pair of shutter members 46 are provided with stepped convex surfaces 47 corresponding with the concave formation 45 of the plate 36 and are engaged therewith at opposite ends of the exposure opening of the plate 36 for angular movement to vary said exposure opening longitudinally of the guide whereby to vary the exposure of the films in this guide 50 as they are fed therethrough at a uniform rate by uniform rotation of the sprocket comprising the wheels 31. Headed screws 48 are engaged in slots 49, through the plate 36 at the shallower portions of the concave formation 45 and extending longitudinally of the plate, and are screwthreaded into the shutter members 46, whereby these shutter members are adjustably positioned in their 55 said angular movement with respect to the plate 36.

The closure member 33 is provided with an aperture 51 communicating the exposure aperture of the guide plate 36 with the enclosure formed by this closure member and the wheels 31 as hereinbefore described. 70 See Figures 2, 3, and 13. An incandescent electric lamp 52 is disposed within this enclosure between the exposure aperture of the plate 36 and the portion of the shaft 29 between the wheels 31 and aligned with said exposure aperture to provide the printing light at this exposure aperture, and this lamp is mounted in the following manner. See Figures 2, 3, 9, and 10.

The closure member 33 is provided with an internal vertically projecting support 53 which extends in parallelism with the plane of the closure member at the outside thereof. This support member is provided with a large bore 54 therethrough normal to the plane of the wheels 31 and provided with an outwardly facing shoulder 55 adjacent its inner end. Engaged in the bore 54 and against the shoulder 55 for removal outwardly therefrom is an annular socket block 56 of insulating material. Screwthreaded for longitudinal adjustment in the bore of the block 56 is a metal bushing 57 which is bayonet slotted, as designated at 58 in Figure 2, for engagement with radial pins 59 on the usual "single contact" 80 base 61 of the lamp 52. The bushing 57 is flanged at its outer end, and an annular plate 62 is secured against the flanged end of the bushing for angular adjustment with respect thereto by means of headed screws 63 passing through angular slots 64 in the plate 62 and screwthreaded into the flange of the bushing 57. Secured to the plate 62 on the outside thereof, is a handle 65 of insulating material and an electrical spring contact 66 which 85 is insulated from the plate 62 in a usual manner. The handle 65 extends over the center of the plate 62 and the contact 66 underlies the same and contacts the usual center contact 67 of the lamp base 61. The handle 65 provides 90 for the convenient manipulation of the socket just described with the lamp 52 therein through openings 68 formed in the web of the outer wheel 31, and through which openings the socket and lamp 52 thereon may be 95 inserted in or removed from the enclosure formed by the wheels 31 and the closure member 33, the bore 54 of the support 53 permitting passage of the lamp 52 therethrough. The openings 68 are closed by cover members 100 105 110 115 120 125 130 69 which are releasably secured on the outer wheel 31 by headed screws 70 to permit access through these openings.

Electrical contact with the above described socket is established, when the socket is mounted as above described, in the following manner. Bushings 72 of insulating material are secured in bores through the support 53 and disposed in parallelism with the bore 54 and

on diametrically opposite sides of the same. Secured on these bushings by means of headed screws and nuts 73 are electric spring contacts 74 and 75 which are connected to opposite sides of an external source of electrical current in a usual manner. The contact 74 is adapted to overlie and contact the outer face of the plate 62 which is in electrical communication with the metal shell of the lamp base 61 of the lamp 52, which forms one contact thereof, by means of the metal bushing 57. The contact 75 is adapted to overlie the outwardly extending end of the contact 66 which contacts the center contact 67 of the lamp base. Thus is formed an electrical circuit through the lamp 52 when the socket is in one angular position thereof. When it is desired to remove the socket it is given an angular movement to disengage the contact 75 from the contact 66 in which position the contact 74 disengages from the plate 62 by reason of the plate having a portion of its circumference cut away on a chord thereof, as designated at 76 in Figure 10. In this position the socket and lamp 52 thereon may be removed through an opening 68 in the web of the outer wheel 31. Insertion of the socket with the lamp 52 thereon in the enclosure of the wheels 31 and enclosure member 33 is accomplished by inserting them through an opening 68 and passing the lamp through the bore 54 and inserting the socket in the bore 54 with the cutaway portion 76 of the plate 62 registered with the contact 74 and then turning the socket until the contacts 74 and 75 engage respectively the plate 62 and the contact 67.

It will be observed that removal of the lamp 52 from and insertion of the same in the enclosure provided by the wheels 31 and the closure member 33 is effected in a simple and convenient manner. In addition the lamp 52 may be adjusted on the socket on which it is mounted both axially and angularly with respect thereto to properly position the filament of the lamp with respect to the exposure opening of the guide plate 36. The screwthreaded engagement of the bushing 57 with the socket block 56 provides for axial adjustment of the lamp 52 in an obvious manner. The angular adjustment of the plate 62 with respect to the bushing 57, provided by the screws 63 engaged in the slots 64, permits angular adjustment of the lamp by reason of this adjustment permitting a range of angular adjustment of the bushing 57 with respect to a predetermined angular position of the plate 62 when the socket is mounted on the support 53. The lamp 52 may be adjusted on the socket before mounting of the socket in the aforementioned enclosure by means of a suitable setting jig unnecessary to be described.

As hereinbefore described the photographically sensitized or positive film 14 is fed

through the exposure guide formed by the guide plates 9 and the guide member 11 in printing relation with the negative film 13, and the positive film 14 is also fed through the exposure guide formed by the guide plate 36 and the guide member 39 in printing relation with another negative film 44. These exposure guides are adapted for exposing the photographically sensitized or positive film 14 in printing relation with the respective negative films 13 and 44 progressively therealong, and, as shown, this progressive printing upon the positive film 14 from the two negative films 13 and 44 is effected simultaneously. See Figure 1.

Accordingly the positive film 14 is fed from a feed spool 77 by means of a driven continuous feed sprocket 78, after which it passes through a tensioning device, generally indicated at 79, to the exposure guide, comprising the guide plate 36 and guide member 39, through which it is fed continuously at a uniform rate in superposed printing relation with the negative film 44 past the exposure aperture of this guide by means of the driven continuous feed sprocket comprising the wheels 31 for printing by means of the light provided by the lamp 52. Leaving this exposure guide the positive film is fed by a driven continuous feed sprocket 81, after which it passes through a tensioning device, generally indicated at 82, to the exposure guide, comprising the guide plates 9 and the guide member 11, through which it is fed continuously at a uniform rate in superposed printing relation with the negative film 13 past the exposure aperture of this guide by means of the driven continuous feed sprocket comprising the wheels 7 for printing by means of the light provided by the lamp 3. Leaving this last mentioned exposure guide the positive film is fed by a driven continuous feed sprocket 83, after which it is wound upon a driven winding spool 84.

The negative film 44 is fed from a feed spool 85 by means of the aforementioned driven sprocket 78, after which it passes through a tensioning device, generally indicated at 86, to the exposure guide, comprising the guide plate 36 and guide member 39, through which it is fed, as aforesaid, by the driven sprocket, comprising the wheels 31. Leaving this exposure guide the negative film 44 is fed by a driven continuous feed sprocket 87, after which it is wound upon a driven winding spool 88.

The negative film 13 is fed from a feed spool 89 by means of the aforementioned driven sprocket 81, after which it passes through a tensioning device, generally indicated at 91, to the exposure guide, comprising the guide plates 9 and the guide member 11, through which it is fed, as aforesaid, by the driven sprocket, comprising the wheels 7. Leaving this exposure guide the negative film 13

13 is fed by the aforementioned driven sprocket 83, after which it is wound upon a driven winding spool 92.

The sprockets 78, 81, 83, 87, the sprocket 5 comprising the wheels 31 and the sprocket comprising the wheels 7 are connected to be driven at equal peripheral speeds by means of a gear train 93 enclosed within the gear casing 28.

10 An electric motor 94, secured on a bracket of the pedestal 1, drives the gear train 93 through the medium of a belt and pulley driving device, generally indicated at 95, including a belt 96 which is trained over pulleys 97 secured with the winding spools 84 and 92 to drive the same. The winding spool 88 is driven from the upper portion of the gear train 93 by means of a belt and pulley driving device 98. The winding and feed 15 spools of the machine are mounted in a suitable manner upon a pipe frame 99 secured with the frame of the machine and with the pedestal.

The exposure apertures of the aforementioned exposure guides are adapted to expose 25 different adjoining longitudinal sections of the positive film 14 in printing relation with respective portions of the negative films 13 and 44, and each of the exposure guides are 30 masked to prevent exposure thereby of the longitudinal section of the positive film which is exposed by the other exposure guide.

Accordingly, the exposure aperture of the exposure guide, comprising the guide plate 35 36 and the guide member 39, extends laterally of the guide from the inner wheel 31 outwardly therefrom to define a comparatively narrow longitudinal side section of the picture portion of the film in this guide, the 40 exposure aperture of this guide being limited laterally by the inner wheel 31 and the longitudinal edge 100 of the deeper portion of the concave formation 45. See Figures 2 and 11. Accordingly the remaining and comparatively wide longitudinal section of the 45 picture portion of the films in this guide are masked from exposure in this guide, the guide plate 36 having no light opening therein between the outer edge 100 of the exposure 50 opening thereof and the outer wheel 31, whereby the corresponding longitudinal section of the positive film is not exposed in this guide. Likewise the only part of the negative film 44 which is effective to print upon the positive film 14 in the last mentioned exposure 55 guide is that longitudinal section thereof which corresponds with the exposure aperture of this guide, i. e., the portion defined by the inner wheel 31 and the edge 100 of the 60 plate 36.

The exposure aperture of the exposure guide, comprising the guide plates 9 and the guide member 11, extending laterally of this 65 guide from the outer wheel 7 to the outer edge of the flange of the inner wheel 7, which

flange is extended outwardly, as designated at 101, to mask and thereby prevent exposure in this guide, of the longitudinal side section of the films in this guide corresponding with the portion of the films exposed in the guide, comprising the guide plate 36 and the guide member 39, between the inner wheel 31 and the edge 100 of the guide plate 36. 70

Thus are the two longitudinal sections of the positive film 14 printed simultaneously 75 respectively from the negative films 13 and 44 progressively therealong.

The negative film 44, which prints the comparatively narrow longitudinal section of the positive film 14, preferably bears a visual sound record which is printed upon the positive film along said section thereof for translation by suitable means to reproduce from the developed positive film the original sounds recorded on the corresponding longitudinal section of the negative film 44. 80

The negative film 13, which prints the comparatively wide longitudinal section of the positive film 14, preferably bears motion pictures which are printed upon the positive film along said section thereof for the projection of motion pictures from the developed positive film by a suitable motion picture projecting machine. 85

The visual sound record and the motion 90 pictures printed upon the positive film 14 are related for the exhibiting of the so-called talking motion pictures.

Figure 6 shows a portion of the positive film 14 after printing and development, in which 102 designates the comparatively narrow longitudinal section thereof upon which the sound record is printed, and 103 designates the comparatively wide longitudinal section thereof upon which the motion 100 pictures are printed. 105

Figure 7 shows a portion of the motion picture bearing negative film 13, in which 104 designates the comparatively wide longitudinal section thereof upon which the motion pictures are disposed and which corresponds with the section 103 of the positive film 14. 110

Figure 8 shows a portion of the visual sound record bearing negative film 44, in which 105 designates the comparatively narrow longitudinal section thereof upon which the sound record is disposed and which corresponds with the section 102 of the positive film 14. 115

It will be observed that means is provided for independently varying the printing light at the several exposure apertures, with the result that the sound record and the motion pictures may be printed upon the positive 120 film under different light conditions to effect desired intensities of the images on the two longitudinal sections of this film. The adjustment of the printing light for the printing of the sound record, as shown, is effected 125

by the adjustment of the shutter members 46 to vary the associated exposure aperture longitudinally of the movement of the film, it being not necessary to change this adjustment 5 during the printing operation for the reason that the sound record is photographed upon the negative film 44 under manually controlled conditions whereby a uniform intensity of the negative is obtainable.

10 The adjustment of the printing light for the printing of the motion pictures is variable by adjustment of either the shutter member 16 or the shutter member 25. Preferably adjustment of the shutter member 16 is 15 more or less permanent, say for the printing from an entire negative film while the shutter member 25 is adjusted during the printing operation to vary the printing light to effect the printing of the motion pictures 20 upon the positive film with a uniform density, it being noted that it is usual that different motion picture scenes are photographed upon the corresponding negative film under different light conditions with resulting different 25 densities of the different scenes on the negative.

It is desirable that the printing operation or the movement of the films, particularly in the printing of the second record, shall be 30 continuous and uninterrupted.

Accordingly the adjustment of the shutter member 25 is effected during the printing operation and without interrupting the printing operation or the movement of the 35 films. The various means for so adjusting the shutter 25 are well known, and conform basically with that described and claimed in my U. S. Letters Patent Reissue No. 14,799, reissued February 3, 1920, for improvement 40 in photographic printing apparatus, and as shown generally herein consists of an electric circuit breaker 106, see Figure 1, under the control of an edge of the motion picture bearing negative film 13, which edge is notched, 45 as designated at 107 in Figure 7, at intervals therealong corresponding with the light changes to be made in printing from this film, an adjusting device 108, see Figure 1, connected with the arm 26 for variably adjusting 50 the shutter 25 and under the control of the circuit breaker 106 to function when the circuit breaker is actuated by a notch 107 of the film 13; and a manually adjusted device 109 for predeterminedly setting the adjusting 55 device 108 to effect a desired adjustment of the shutter 25 when the circuit breaker is actuated by a notch 107 of the film 13 to cause the adjusting device 108 to function, the device 109 being reset after each adjustment of 60 the shutter 25 in a predetermined manner.

While I have described and shown one form of my invention I do not wish to be limited to the precise details of construction shown, as changes may readily be made without departing from the spirit of my invention,

but having thus described my invention, I claim as new and desire to secure by Letters Patent the following:

1. In a photographic printing machine the combination with a revoluble film feed sprocket comprising two axially spaced wheels at least one of which is peripherally toothed and an axial spindle extending therebetween, of a stationary film guide of arcal formation disposed correspondingly with the periphery of said sprocket for guiding superposed films engaged on said sprocket and provided with an exposure aperture between said wheels and facing inwardly of the sprocket, a stationary closure member forming an enclosure between said wheels and communicating with said exposure aperture, and an incandescent electric lamp within said enclosure between said spindle and exposure aperture and carried by said closure member. 75

2. In a photographic printing machine the combination with a frame, of a spindle revolubly mounted on said frame and projecting therefrom, a film feed sprocket on the projecting portion of said spindle and comprising axially spaced wheels at least one of which is peripherally toothed, a film guide disposed for guiding superposed films engaged on said sprocket and provided with an exposure aperture between said wheels and facing inwardly of the sprocket, a closure member forming an enclosure between said wheels and communicating with said exposure aperture, a source of photographic light within said enclosure and carried by said closure member, and means whereby said closure member is carried by said frame and extending from said closure member between said wheels and outwardly thereof. 90

3. In a photographic printing machine the combination with a frame, of a spindle revolubly mounted on said frame and projecting therefrom, a film feed sprocket on the projecting portion of said spindle and comprising axially spaced wheels having the peripheral portions thereof projected toward each other and at least one of which is peripherally toothed, a stationary film guide of arcal formation disposed correspondingly with the periphery of said sprocket for guiding superposed films engaged on said sprocket and provided with an exposure aperture between said wheels and facing inwardly of the sprocket, a stationary closure member of generally circular form disposed between said wheels and underlying said projected peripheral portions of said wheels and forming an enclosure therewith communicating with said exposure aperture, an incandescent electrical lamp within said enclosure between said spindle and exposure aperture and carried by said closure member, and means whereby said closure member is carried by said frame and extending from said closure 100

member between said wheels and outwardly thereof.

4. In a photographic film printing machine the combination with a revoluble film feed sprocket comprising two axially spaced 5 wheels at least one of which is peripherally toothed, of a stationary closure member forming an enclosure with said wheels between the same, means whereby an incandescent electric lamp is detachably mounted 10 on said closure member within said enclosure, one of said wheels having an opening through the web thereof through which said lamp may be inserted in or removed from said enclosure, 15 and means closing said opening and adapted to permit access through said opening.

5. In a photographic film printing machine the combination with a revoluble film feed sprocket comprising two axially spaced 20 wheels at least one of which is peripherally toothed, of a stationary closure member forming an enclosure with said wheels between the same, an incandescent electric lamp socket, a mounting on said closure 25 member within said enclosure for the detachable mounting thereon of said socket, one of said wheels having an opening through the web thereof through which said socket with an incandescent electric lamp thereon 30 may be inserted in or removed from said enclosure, and means closing said opening and adapted to permit access through said opening.

6. In a photographic film printing machine the combination with a revoluble film feed sprocket comprising two axially spaced 35 wheels at least one of which is peripherally toothed, of a stationary closure member forming an enclosure with said wheels between 40 the same, an incandescent electric lamp socket provided with circuit contacts, a mounting on said closure member within said enclosure for the detachable mounting thereon of said socket, circuit contacts on said closure member adapted to releasably engage said circuit 45 contacts of the socket when the socket is engaged on said mounting, one of said wheels having an opening through the web thereof through which said socket with an incandescent 50 electric lamp thereon may be inserted in or removed from said enclosure, and means closing said opening and adapted to permit access through said opening.

7. In a photographic film printing machine the combination with a revoluble film feed sprocket comprising two axially spaced 55 wheels at least one of which is peripherally toothed, of a stationary closure member forming an enclosure with said wheels between 60 the same, an incandescent electric lamp socket, means for adjustably mounting an incandescent electric lamp on said socket, means whereby said socket is mounted in a predetermined position on said closure member 65 within said enclosure, one of said wheels

having an opening in the web thereof through which the socket and the lamp thereon may be inserted in or removed from said enclosure, and means closing said opening and adapted to permit access through said opening.

8. In a photographic film printing machine the combination with a revoluble feed sprocket comprising two axially spaced 70 wheels at least one of which is peripherally toothed, of a stationary closure member forming an enclosure with said wheels between the same and provided with a shoulered bore within said enclosure, an incandescent electric lamp socket removably engaged in said bore and against said shoulder for angular movement therein, means on said socket for adjustably positioning an incandescent electric lamp mounted thereon, circuit contacts carried with said closure member and said socket adapted for contact in a predetermined angular position of said socket in said bore and disengaging in another angular position of said socket for removal of the socket from said bore, one of said wheels 80 having an opening in the web thereof through which the socket and the lamp mounted thereon may be inserted in or removed from said enclosure, and means closing said opening and adapted to permit access through said opening.

9. In a photographic printing machine the combination with a constant feed film exposure guide including a film face guide member provided with an exposure opening and with a concave surface facing oppositely from film in the guide and extending longitudinally of the guide and longitudinally aligned with said exposure opening, a shutter member provided with a corresponding convex surface engaged with said concave surface for angular movement to vary said exposure opening, and means for adjustably positioning said shutter member in said angular movement to said guide member.

10. In a photographic printing machine the combination with a constant feed film guide including a film face guide member having a concave formation facing oppositely from film in the guide and extending longitudinally of the guide member and forming an intermediate exposure opening therethrough, a pair of shutter members provided with corresponding convex surfaces engaged with said concave formation at opposite ends of said exposure opening for angular movement to vary said exposure opening, and means for adjustably positioning said shutter members in said angular movement with respect to said guide member.

11. In a photographic printing machine the combination with a constant feed film guide including a film face guide member having its film face guide surface composed of an intermediate longitudinally extending

convex portion and end portions tangent thereto and provided with a concave formation facing oppositely from film in the guide and continuing the arc of said intermediate portion and forming an exposure opening at said intermediate portion, a pair of shutter members provided with corresponding convex surfaces engaged with said concave formation at opposite ends of said exposure opening for angular movement to vary said exposure opening, and means for adjustably positioning said shutter members in said angular movement with respect to said guide member.

15 In witness whereof I hereunto affix my signature this 13th day of August, 1927.

ALBERT S. HOWELL.
